J. R. FRANCIS

HEAT CONTROL FOR INTERNAL COMBUSTION ENGINES

Filed Nov. 18, 1920

UNITED STATES PATENT OFFICE.

JACOB RICHARD FRANCIS, OF FLINT, MICHIGAN.

HEAT CONTROL FOR INTERNAL-COMBUSTION ENGINES.

Application filed November 18, 1920. Serial No. 424,915.

This invention relates to certain new and useful improvements in heat control for internal combustion engines, the object being to provide means controlled by the velocity 5 of air entering the charge forming device for regulating the temperature of the charge delivered to the internal combustion engine.

Another and further object of the invention is to provide a construction which is 10 very simple, the same being capable of being applied to several of the well known types of carburetors now in use in which a heating chamber surrounds a portion of the carbureting passage of the charge forming 15 device.

Other and further objects and advantages 20 of the invention will be hereinafter set forth and the novel features thereof defined by the appended claims.

20 In the drawings,

Figure 1 is a side elevation of an internal combustion engine showing the application 25 of my improved construction of heat control, partly in section; and

Figure 2 is an end elevation showing the 30 vane or blade within the air inlet and carburetor and in dotted line the valve in the valve casing.

In the drawings 1 indicates an internal 35 combustion engine, 2 the exhaust manifold and 3 the intake manifold which is herein shown connected directly to the upper end of a charge forming device 4 having a heating jacket 5 surrounding the upper end

thereof which is provided with inlet nipples 6 and outlet nipples 7 which are connected to the inlet and outlet nipples 8 and 9 of the valve casing 10 disposed in the exhaust line pipe 11 adjacent the exhaust manifold

40 2. The valve casing 10 is provided with a valve stem 12 carrying a valve 13 in order to divert the exhaust gases through the heating chamber formed by the jacket 5 surrounding the carbureting passage of the carburetor or charge forming device.

The charge forming device 4 is provided 45 with an air inlet pipe 13' enlarged as shown at 14 to receive a blade or vane 15 fixed on a shaft 16 pivotally mounted in the enlarged portion 14 of the air inlet pipe 13' which vane is adapted to be normally held in the path of the incoming air and be acted upon thereby so as to swing the blade. The shaft 16 carries an arm 17 having a link 18 connected thereto provided with a hooked end which is adapted to be mounted in one

of the openings 19 of an arm 20 fixed on the valve stem 12 whereby the valve 13 will be operated by the movement of the blade or vane 15. In full lines the normal position 50 of the blade is illustrated and in dotted lines the position of the blade when the velocity of air passing through the carbureting passage has been sufficient to swing the same on its axis and it will be seen that when the motor is running at high speed the blade is swung into such a position that the valve 13 is moved into full open position in order to allow the exhaust gases to pass directly through the exhaust line pipe to the muffler 70 in the ordinary manner. This prevents the overheating of the explosive charge in its passage to the engine.

When the motor is running at slow or intermediate speed the velocity is insufficient 75 to swing the blade into full closed position and a portion of the exhaust gases are diverted into the heating jacket to maintain the charge at the proper temperature. As the speed of the motor increases and the temperature rises, the velocity of the incoming air increases and through its connection with the valve, the volume of exhaust gases delivered to the heating chamber are gradually diminished and it will be seen that by 80 this construction the velocity of the air entering the charge forming device controls the application of heat.

What I claim is:—

1. An internal combustion engine having 90 an exhaust pipe, intake manifold and charge forming device connected thereto, a heater arranged to heat the charge in its passage from the charge forming device to the engine in communication with said exhaust pipe 95 through unclosable passages, said charge forming device being provided with an air inlet, a vane mounted to swing within said air inlet, a valve arranged in the exhaust line pipe for controlling the passage of 100 exhaust gases to said heater and an adjustable connection between said vane and said valve controlling the passage of exhaust gases to said heater by the velocity of air entering said charge forming device. 105

2. An internal combustion engine having an exhaust pipe, intake manifold and charge forming device connected thereto, a heater arranged to heat the charge in its passage to the engine, said heater being in 110 communication with said exhaust pipe through unclosable passages, a valve

mounted in said exhaust pipe, said charge forming device being provided with an air inlet pipe, a shaft mounted in said pipe carrying a vane disposed in the path of travel of the air passing through said charge forming device, an arm carried by said shaft, and a link connecting said arm to said valve for controlling the position of said valve by the velocity of air entering said charge forming device.

3. An internal combustion engine having an exhaust pipe, intake manifold and charge forming device connected thereto, a heater arranged to heat the charge in its passage to the internal combustion engine having inlet and outlet pipes in communication with the exhaust pipe, a valve disposed in said exhaust pipe between the inlet and outlet thereof, said valve having an arm provided with a series of openings and a pivoted vane disposed within the air inlet pipe of said charge forming device having an arm carrying a link adjustably connected to the arm of said valve for controlling the passage of exhaust gases to said

heater by the velocity of air passing into said charge forming device.

4. An internal combustion engine having an exhaust pipe, intake manifold and charge forming device connected thereto, a heater 30 arranged to heat the charge in its passage to the internal combustion engine having inlet and outlet pipes connected to the exhaust pipe, a valve disposed in said exhaust pipe having an arm provided with a series 35 of openings, said charge forming device having an air inlet pipe enlarged at its outer end, a shaft mounted in said enlargement, a blade carried by said shaft disposed in the path of travel of the air passing 40 through said air inlet, an arm carried by said shaft, and a link connected to said arm having a hooked end adapted to be positioned within one of the openings of the arm of said valve for controlling the position of the valve by the velocity of air passing through said charge forming device.

In testimony whereof I have hereunto affixed my signature.

JACOB RICHARD FRANCIS.
